ACID DYE COMPOSITION FOR HUMAN HAIR
Louis L. Lerner, Chicago, and Helen E. Oberstar, Glen
Ellyn, Ill., assignors to The Gillette Company, Boston,
Mass., a corporation of Delaware
No Drawing. Filed Aug. 4, 1961, Ser. No. 129,251
2 Claims. (Cl. 167—88)

This invention relates to a dye composition suitable for dyeing keratinous material such as human hair and pertains more specifically to such a dye composition containing acid dyes together with sufficient free base to provide a pH from 8.5 to 12.5 in aqueous solution.

One object of the present invention is to provide a dye composition effective for dyeing keratinous material such as human hair, the composition being of such a nature that a mixture of two or more dyes in the composition is absorbed selectively in predetermined ratio by the hair so that predictable and accurately reproducible results are obtained.

Another object is to provide such a dye composition containing acid dyes capable of dyeing human hair from an aqueous alkaline solution having a pH from 8.5 to 12.5.

Still another object is to provide such a dye composition in which the dyes are medically safe, for example U.S. certified colors.

A further object is to provide a combined bleaching-dyeing composition effective for dyeing human hair to a predictable and reproducible color from an aqueous alkaline medium.

Other objects will be apparent from the description which follows.

While hair dye which is applied to the hair and not to any other part of the body has no toxic effect, it does occasionally come into contact with the skin accidentally so that, in order to avoid problems of possible toxicity and/or sensitization, it is desirable to use a medically safe dye such as a U.S. certified color rather than an uncertified coal-tar dye. However, most of such medically safe dyes, for example most U.S. certified colors, are acid dyes; and it has not been possible to obtain the desired range of colors from the certified colors which are not acid dyes. In order to achieve lighter and more intense colors than are naturally present in the hair, it is also desirable to bleach the hair, preferably at the same time that the dyeing operation takes place, using a single combined bleaching-dyeing composition. The bleaching agents of choice for use on human hair are peroxides, but these materials are effective as bleaching agents for hair only in aqueous alkaline solution, and it has generally been considered impossible to obtain effective dyeing from an alkaline medium using acid dyes.

It has now been discovered that by a suitable combination of ingredients in addition to the acid dye itself, it is possible to obtain highly satisfactory hair dyeing from such compositions when they are employed in aqueous alkaline media. Moreover, it has been found that the dye compositions of the present invention offer the important advantage that the extent of absorption of dyes from a mixture containing a predetermined ratio of dyes is predictable and accurately reproducible for any given type of hair.

The dye compositions of the present invention include, in addition to the dye or mixture of dyes which includes acid dyes, a non-dyeing salt of a cation which is either monovalent or bivalent, and an alkaline material in an amount sufficient to provide a pH of 8.5 to 12.5 upon dissolution of the composition in water. The compositions may also include, in a preferred embodiment, from 20% to 400%, based on the total weight of the dye and

2

the salt, of a non-dyeing organic material having certain solubility characteristics.

The dyes which are effective in the present invention are those conventionally known as acid dyes; that is, those organic dyes which dye animal fibers directly from an acidic dye bath. Included among these dyes are most of the U.S. certified colors, which are the dyes of choice.

The salts which may be employed in conjunction with the dye or mixture of dyes include a wide variety of organic and inorganic salts which are inert to the dyes and other ingredients of the composition and which are non-reactive with the hair. When organic salts are employed, they must contain no chains of carbon atoms exceeding six carbon atoms in length. Among such salts are those of mono- and di-valent cations such as the alkali and alkaline earth metals, ammonia, lower alkylamines containing from 1 to 4 carbon atoms, and mono-, di-, and tri-alkanolamines in which each alkanol group contains from 2 to 3 carbon atoms. The salts include those having such anions as the chlorides, bromides, sulfates, acetates, borates, nitrates, citrates, lactates, bromates, chlorates, etc. The salts which are effective are those which are water-soluble; i.e., those which are soluble to the extent of 0.1% by weight or more in water at 25° C. The salt must be present in the composition in an amount at least equal to the weight of the dye, the ratio of dye to salt being from 1:1 to 1:20,000 by weight.

The third essential ingredient of the composition is a free base in an amount sufficient to produce a pH from 8.5 to 12.5 when the composition is dissolved in water. When the dye composition is provided in the form of a dry solid material to be dissolved in an aqueous medium to form the dye bath, it is preferred that the free base be a solid material such as sodium hydroxide, sodium carbonate, or 2-amino-2-methyl-1,3-propanediol. The dye composition may, however, be provided in the form of an aqueous solution, in which case it is also possible to employ such free bases as ammonium hydroxide, monoethanolamine, and the like.

While dye compositions containing the dye, salt, and free base as described above are effective for the purpose of the present invention when applied to the hair in the form of an aqueous solution, optimum results are obtained by adding to the composition from 20% to 200%, based on the total weight of dye and salt, of a non-dyeing organic material having certain solubility characteristics as hereinafter defined. Up to 400% by weight of this material, based on the weight of dye and salt, may be added if desired. The organic material may be either liquid or solid at ordinary temperatures, but must not be completely miscible at ordinary temperatures with the aqueous dye, salt, free base compositions described above. It may be substantially completely immiscible with or substantially insoluble in such compositions, or it may be miscible with them only to a limited extent. In any event, it must possess a water solubility so limited that when mixed with an aqueous salt solution in the ratio of 4 parts of the organic material to 10 parts of water to 1.4 parts salt by weight at 25° C., it forms a separate phase and does not completely dissolve in or mix with aqueous phase. In addition, the organic material must have a solvent power for the dye or mixture of dyes in the dye composition which is approximately equal to the solvent power of water. This solvent power can be determined by dissolving the dye composition—including the dye or dye mixture, the salt, and the free base—in aqueous solution, then placing in contact with the aqueous solution sufficient organic material so that a separate phase is present, and allowing the two phases to remain in contact with each other at 25° C. for three hours. Extent of dye extraction can best be determined visually

when the dye concentration in the aqueous phase at the beginning of the test is quite low; a dye concentration of 0.0005% by weight in the aqueous phase has proved to be very satisfactory. If under these conditions visual inspection of the two layers show that the organic material phase has extracted a portion only of the dye from the aqueous phase, then the organic material is satisfactory for the purpose of the present invention. On the other hand, if the organic phase has extracted none of the dye from the aqueous phase or if it has extracted substantially all of the dye from the aqueous phase, the organic material is not satisfactory for the purpose of the present invention.

Among organic materials which have been found satisfactory for purposes of the present invention are such organic alcohols as n-butyl alcohol, n-amyl alcohol, n-octyl alcohol, benzyl alcohol, terephthalyl alcohol, phenyl ethyl alcohol, and the like, cyclohexanone, tetrahydrofuran, aniline, chlorobenzene, camphor, xylene, toluene, and various other materials. For most purposes the alcohols are preferred, benzyl alcohol being the material of choice. The amount of organic material may vary from 0% to 400%, based on the total weight of the dye and the salt.

As indicated above, the dye composition may be provided in dry solid form to be dissolved in an aqueous medium to form the dye bath, in which case each of the ingredients is itself preferably solid. The dye composition may also conveniently be supplied to the consumer in the form of a paste, cream, or free-flowing aqueous solution, in which case one or more ingredients may be liquids. It is also possible to employ hair-bleaching agents in combination with the remaining ingredients in the present invention to provide combined bleaching-dyeing compositions. When the dye composition including free base is provided in dry solid form, the bleaching agent, in solid form, may be stored in admixture with the remainder of the composition. When the dye composition is provided in the form of paste, cream or solution, however, the bleaching agent, whether solid or not, must be kept separate from the remainder of the composition until shortly before use.

Bleaching agents which may be used effectively in combined bleaching-dyeing compositions include urea peroxide and sodium carbonate peroxide, both of which may be added to the composition in dry solid form, and hydrogen peroxide which may be employed in the form of a paste, cream or free-flowing aqueous solution. When the bleaching agent is hydrogen peroxide, it must be supplied in an aqueous medium, it must be packaged separately from the dye or mixture of dyes, and it must be maintained at an acidic pH. Consequently, the free base must under these conditions be packaged separately from the bleaching agent, being packaged either by itself or in admixture with the dye composition. The amount of free base should be such, as is readily determined by those skilled in the art, as to provide a pH from 8.5 to 12.5 in the aqueous dye bath in the form in which it is applied to the hair.

The water content of the compositions may vary over a wide range. It will be understood that in some cases it may be desirable to supply the dye composition in the form of a highly concentrated aqueous solution adapted to be diluted with additional water by the ultimate consumer immediately prior to use. The water content of the aqueous composition in the form in which it is actually applied to the hair for dyeing purposes may also vary over a considerable range, depending upon the intensity of color desired and the length of time available for maintaining the dye bath in contact with the hair, as well as upon the temperature at which the dyeing operation is carried out. In general, the water content of the dye bath in the form in which it is applied to the hair will range from 65% to 90% by weight.

Such optional ingredients as are commonly employed in conventional hair dye and hair bleach compositions may also be employed in the compositions of the present invention. Among such additives are perfumes, opacifiers, and thickeners, e.g., ethoxylated fatty alcohols, carboxylated vinyl polymers, ethoxylated tallow alcohols, stabilizers, etc. However, it is essential that the composition contain no reducing agents which react with the hair both because they might tend to damage the hair and because they are incompatible with the oxidizing bleaching agents.

The following specific examples are intended to illustrate more clearly the nature of the invention without placing any restriction upon its scope.

Example 1

The following composition was prepared, in which the parts are by weight:

	Parts
D & C Brown No. 1 (C.I. No. 20170)	0.5
Benzyl alcohol	3.8
Sodium sulfate	4.0
Ammonium hydroxide (28° Bé.)	4.0
Water, to make	100.0

The composition was applied to white hair by means of a sponge and allowed to stand for 15 minutes at 26° C., after which the hair was rinsed in water, shampooed twice, and finally rinsed again with water. The hair showed a desirable brownish shade.

Example 2

The following composition was prepared, in which the parts are by weight:

	Parts
Ext. D & C Red No. 13 (C.I. No. 27290)	0.5
N-butanol	10.7
Sodium sulfate	5.0
Ammonium hydroxide (28° Bé.)	4.0
Water, to make	100.0

This composition was applied to hair as described in Example 1, the result being a red coloration.

Example 3

The following composition was prepared, in which the parts are by weight:

	Parts
D & C Brown No. 1 (C.I. No. 20170)	0.5
Benzyl alcohol	3.8
Lithium bromide	4.0
Ammonium hydroxide (28° Bé.)	4.0
Water, to make	100.0

The composition was employed to dye white hair using the procedure described in Example 1; the finished hair was found to exhibit a light brown color.

Example 4

The following composition was prepared, in which the parts are by weight:

	Parts
D & C Brown No. 1 (C.I. No. 20170)	0.5
N-amyl alcohol	3.0
Sodium sulfate	4.0
Ammonium hydroxide (28° Bé.)	4.0
Water, to make	100.0

The composition was employed to dye white hair by the procedure of Example 1; the finished hair was found to exhibit a light brown color similar to that produced in Example 3 above.

5

Example 5

The following compositions were prepared, in which the parts are by weight:

	Parts	5
D & C Brown No. 1 (C.I. No. 20170) -----	0.5	
Sodium sulfate -----	5.0	
Ammonium hydroxide (28° Bé.) -----	4.0	
Non-dyeing organic material, as specified in the following table.		
Water, to make -----	100.0	10
Non-dyeing organic material:		
Benzyl alcohol -----	1.9	
Benzyl alcohol -----	3.8	
Benzyl alcohol -----	7.6	
Tetrahydrofuran -----	5.0	
Tetrahydrofuran -----	10.0	
Tetrahydrofuran -----	20.0	
N-butanol -----	5.0	
N-butanol -----	10.7	
N-butanol -----	20.0	

Each dye composition containing the particular non-dyeing organic material in the quantity specified was employed to dye white hair by the procedure of Example 1 above. In each case the dye composition was highly effective in producing a distinct and intense color in the white hair.

Example 6

The following compositions were prepared, in which the parts are by weight:

	Parts	
D & C Brown No. 1 (C.I. No. 20170) -----	0.5	
Benzyl alcohol -----	3.8	
Ammonium hydroxide (28° Bé.) -----	4.0	
Non-dyeing salt, as specified in the following table.		
Water, to make -----	100.0	
Non-dyeing salt:		
Sodium sulfate -----	2.0	
Sodium sulfate -----	6.0	
Sodium sulfate -----	15.0	
Magnesium sulfate -----	2.0	
Magnesium sulfate -----	10.0	
Ammonium chloride -----	2.0	
Ammonium chloride -----	10.0	
Sodium sulfite -----	2.0	
Sodium sulfite -----	10.0	
Sodium bromate -----	2.0	
Sodium bromate -----	10.0	

When used for dyeing white hair in the procedure described in Example 1, each of the foregoing compositions containing the salt designated in the amount specified produced intense coloration.

Example 7

The following compositions were prepared, in which the parts are by weight:

	Parts	
Ext. D & C Violet No. 2 (C.I. No. 60730) -----	0.5	
Benzyl alcohol -----	3.8	
Ammonium hydroxide (28° Bé.) -----	4.0	
Non-dyeing salt, as shown in the following table.		
Water, to make -----	100.0	
Non-dyeing salt:		
Sodium sulfate -----	2.0	
Sodium sulfate -----	6.0	
Sodium sulfate -----	15.0	
Ammonium chloride -----	2.0	
Ammonium chloride -----	10.0	
Sodium sulfite -----	2.0	
Sodium sulfite -----	10.0	
Sodium bromate -----	2.0	
Sodium bromate -----	10.0	

In each case when employed in the procedure described in Example 1 above, the dye compositions produced very marked and intense colorations in white hair.

6

Example 8

The following compositions were prepared, in which the parts are by weight:

	Parts	
D & C Brown No. 1 (C.I. No. 20170) -----	0.5	
Benzyl alcohol -----	3.8	
Sodium sulfate -----	5.0	
Free base, as shown in the following table.		
Water, to make -----	100.0	
Free base:		
Ammonium hydroxide (28° Bé.) -----	1.0	
Ammonium hydroxide (28° Bé.) -----	2.0	
Ammonium hydroxide (28° Bé.) -----	4.0	
Ammonium hydroxide (28° Bé.) -----	6.0	
Monoethanolamine -----	1.0	
Monoethanolamine -----	4.0	
Sodium hydroxide -----	1.0	

In the case of each of Examples 1 to 8, the procedure described in Example 1 above produced the desired intense coloration in the hair. The composition containing sodium hydroxide produced a stronger coloration than did the others and exhibited a higher pH, about 12.0-12.1, than did the compositions containing the other free bases, which had a pH of about 11.7 (ammonium hydroxide) and 11.2 (monoethanolamine), respectively.

Similar results were obtained when the 3.8 parts of benzyl alcohol in the foregoing compositions were replaced by 1.0 part of N-hexane.

Example 9

The following composition was prepared, in which the parts are by weight:

	Parts	
D & C Black No. 1 (C.I. No. 20470) -----	0.0133	
Ext. D & C Red No. 13 (C.I. No. 27290) -----	0.0033	
Thickener comprising high molecular weight carboxylated vinyl polymer (Carbopol 934) -----	2.0	
Ammonium hydroxide (28° Bé.) -----	5.0	
Benzyl alcohol -----	3.8	
Sodium sulfate, anhydrous -----	4.0	
Water -----	85.0	

The composition was applied to white hair with a polyurethane sponge over a period of 2½ to 3½ minutes, then left on the hair for 5 to 6 minutes at room temperature, after which the head was rinsed with water, given two sudsings with a commercial shampoo, and again rinsed with water. The finished hair had a pale, attractive, blue-gray color which exhibited very satisfactory permanency over a three to four week period, during which the hair was frequently shampooed.

Example 10

The following composition was prepared, in which the parts are by weight:

	Parts	
D & C Brown No. 1 (C.I. No. 20170) -----	0.2045	
Ext. D & C Red No. 13 (C.I. No. 27290) -----	0.2275	
Ext. D & C Violet No. 2 (C.I. No. 60730) -----	0.2275	
Thickener comprising high molecular weight carboxylated vinyl polymer (Carbopol 934) -----	2.0	
Ammonium hydroxide (28° Bé.) -----	5.0	
Benzyl alcohol -----	3.8	
Sodium sulfate, anhydrous -----	4.0	
Water -----	85.0	

The creamy composition which resulted from this preparation was applied to a head of hair which has a fading, graying, light brownish-red color by means of a polyurethane sponge over a period of 5 minutes and allowed to remain on the air for an additional 5 minutes at

room temperature, after which the head was rinsed with water, given two sudsings with a commercial shampoo, and again rinsed with water. The result was an attractive titian color which exhibited satisfactory permanency over a four-to six-week period with frequent shampooing.

Example 11

The following composition was prepared, in which the parts are by weight:

	Parts
D & C Brown No. 1 (C.I. No. 20170)	0.8
Ext. D & C Violet No. 2 (C.I. No. 60730)	0.2
Thickener comprising high molecular weight carboxylated vinyl polymer (Carbopol 934)	2.0
Benzyl alcohol	8.0
Ammonium hydroxide (28° Bé.)	8.0
Sodium sulfate, anhydrous	8.0
Water	73.0

This composition was mixed in equal volumes with an aqueous solution containing 6% by weight of hydrogen peroxide. The mixture was applied to medium brown colored hair and allowed to remain in contact with the hair for 15 minutes at room temperature, after which the hair was rinsed with water, sudsed twice with a commercial shampoo, then rinsed again. The finished hair possessed a drab light brown color.

Example 12

The following composition was prepared, in which the parts are by weight:

	Parts
D & C Black No. 1 (C.I. No. 20470)	0.5
Benzyl alcohol	2.0
Ammonium hydroxide (28° Bé.)	4.0
Sodium sulfate	4.0
Water, to make	100.0

The composition was applied to hair and allowed to remain for 15 minutes at room temperature, after which the hair was rinsed with water, sudsed twice with a commercial shampoo, then rinsed again with water. The result was a blue-green color in the hair.

Similar results were obtained when there were added to the foregoing composition 1.8 parts of N-butanol and again when there were added to the composition 1.8 parts of mineral oil instead of butanol.

Example 13

The following composition was prepared, in which the parts are by weight:

	Parts
Ext. D & C Violet No. 2 (C.I. No. 60730)	1.0
Benzyl alcohol	7.6
Sodium sulfate, anhydrous	8.0
Thickener	2.0
Ammonium hydroxide (28° Bé.)	8.4
Water, to make	100.0

This composition was mixed with an equal volume of a creamy peroxide bleach composition containing 6.0 parts by weight of hydrogen peroxide (together with conventional stabilizer), 2.0 parts of ethoxylated tallow alcohol as a thickener, and the balance water.

The mixture was applied to light gray colored hair and allowed to remain for 15 minutes at room temperature, after which the hair was rinsed with water, sudsed twice with a commercial shampoo, and finally rinsed with water again. The hair was found to be dyed to a soft blue-gray shade.

Example 14

The following composition was prepared, in which the parts are by weight:

	Parts
D & C Brown No. 1 (C.I. No. 20170)	0.41
Ext. D & C Violet No. 2 (C.I. No. 60730)	0.60

	Parts
Ext. D & C Red. No. 13 (C.I. No. 27290)	0.50
Benzyl alcohol	8.00
Sodium sulfate, anhydrous	8.00
5 Thickener comprising high molecular weight carboxylated vinyl polymer (Carbopol 934)	2.00
Ammonium hydroxide (28° Bé.)	2.48
Water, to make	100.00

This composition, having a pH of approximately 8.7, was applied to hair and allowed to remain for fifteen minutes at room temperature, after which the hair was rinsed with water, sudsed twice with a commercial shampoo, then rinsed again with water. The result was a titian shade in the hair.

Example 15

The following composition was prepared, in which the parts are by weight:

	Parts
D & C Brown No. 1 (C.I. No. 20170)	0.82
Ext. D & C Violet No. 2 (C.I. No. 60730)	0.09
Ext. D & C Red No. 13 (C.I. No. 27290)	0.09
Benzyl alcohol	8.00
Sodium sulfate, anhydrous	8.00
25 Thickener comprising high molecular weight carboxylated vinyl polymer (Carbopol 934)	2.00
Ammonium hydroxide (28° Bé.)	3.58
Water, to make	100.00

This composition, having a pH of about 9.4, was mixed with an equal volume of a creamy peroxide bleach composition as described in Example 13 above. The mixture was applied to medium brown hair in the manner described in Example 13 above, whereupon the hair was found to have a titian shade.

Example 16

The following composition was prepared, in which the parts are by weight:

	Parts
D & C Black No. 1 (C.I. No. 20470)	0.25
Ext. D & C Red No. 13 (C.I. No. 27290)	0.25
Benzyl alcohol	8.00
Sodium sulfate, anhydrous	8.00
Thickener comprising high molecular weight carboxylated vinyl polymer (Carbopol 934)	2.00
45 Ammonium hydroxide (28° Bé.)	2.58
Water, to make	100.00

This composition, having a pH of about 8.9, was applied to white hair as described in Example 14, producing a soft blue-gray color.

Example 17

The following composition was prepared, in which the parts are by weight:

	Parts
55 D & C Brown No. 1 (C.I. No. 20170)	0.40
Ext. D & C Violet No. 2 (C.I. No. 60730)	0.10
Benzyl alcohol	8.00
Sodium sulfate, anhydrous	8.00
Thickener comprising high molecular weight carboxylated vinyl polymer (Carbopol 934)	2.00
60 Ammonium hydroxide (28° Bé.)	2.58
Water, to make	100.00

This composition, having a pH of about 8.6, was applied to gray hair as described in Example 14 above and was found to produce a brown shade.

Example 18

The following composition was prepared, in which the parts are by weight:

	Parts
D & C Brown No. 1 (C.I. No. 20170)	1.0
Benzyl alcohol	8.0
Sodium sulfate, anhydrous	8.0
Ammonium hydroxide (28° Bé.)	8.0
70 75 Cornstarch	50.0

The mixture was a moist free-flowing powder which could readily be packaged in a metal or plastic foil envelope and which resulted in a solution having a pH of about 10.2 when dissolved in water. It was mixed immediately prior to use with 67 parts by weight of a 3% aqueous hydrogen peroxide solution.

The resulting mixed solution was applied to gray hair by the procedure described in Example 14 and was found to produce a brown shade.

Example 19

The following composition was prepared in which the parts are by weight:

	Parts
D & C Brown No. 1 (C.I. No. 20170) -----	1.0
Benzyl alcohol -----	8.0
Sodium sulfate, anhydrous -----	8.0
Ammonium hydroxide (28° Bé) -----	8.0
White dextrin -----	45.0

The composition was in the form of a moist powder which when dissolved in water produced a solution having a pH of about 9.7. The powdered composition was free-flowing and could readily be packaged in a metal or plastic foil envelope. Immediately before use the powder was dissolved in 45 parts by weight of a 3% hydrogen peroxide solution and the mixture was applied to the hair by the procedure described in Example 12 above, producing a brown coloration in gray or white hair.

Example 20

The following composition was prepared, in which the parts are by weight:

	Parts
D & C Brown No. 1 (C.I. No. 20170) -----	0.5
Benzyl alcohol -----	4.0
Sodium sulfate, anhydrous -----	4.0
Sodium carbonate peroxide -----	12.0
White dextrin -----	20.0

The resulting composition was a completely dry powdered material which could readily be packaged in the same fashion as the powders of Examples 18 and 19 above and which produced when dissolved in 100 parts by weight of water an aqueous solution having a pH of about 9.5. The solution, when applied to gray or white hair by the procedure described in Example 12, above produced a brown shade.

Example 21

The following composition was prepared, in which the parts are by weight:

	Parts
Ext. D & C Violet No. 2 (C.I. No. 60730) -----	0.30
D & C Green No. 5 (C.I. No. 61570) -----	0.03
Sodium sulfate, anhydrous -----	10.00
Ammonium hydroxide (28° Bé) -----	6.90
Water, to make -----	100.00

The solution having the foregoing composition and a pH of about 10.4 was mixed immediately prior to use with an equal volume of a creamy peroxide bleach composition as described in Example 13 above. The mixed solutions upon application to gray hair as described in Example 13 produced a pale blue shade.

Example 22

The following composition was prepared, in which the parts are by weight:

	Parts
D & C Brown No. 1 (C.I. No. 20170) -----	0.32
Ext. D & C Orange No. 3 (C.I. No. 14600) -----	0.35
D & C Black No. 1 (C.I. No. 20470) -----	0.15
Sodium sulfate, anhydrous -----	10.00
Ammonium hydroxide (28° Bé) -----	5.80
Water, to make -----	100.00

The solution, having a pH of about 9.3, was applied to hair by the procedure described in Example 12 above, producing an auburn shade.

Example 23

The following composition was prepared, in which the parts are by weight:

	Parts
Ext. D & C Orange No. 3 (C.I. No. 14600) -----	0.5
D & C Black No. 1 (C.I. No. 20470) -----	0.5
Sodium sulfate, anhydrous -----	10.0
Ammonium hydroxide (28° Bé) -----	6.9
Water, to make -----	100.0

15 The solution, having a pH of about 10.1, was mixed with a creamy peroxide and applied to hair as described in Example 13, except that the head of the individual was wrapped in a turban during the 15-minute period so as to provide a temperature somewhat greater than room temperature. The hair displayed a warm brown shade.

20 Any of the conventional methods of application of dye compositions to hair may be employed in using the compositions of the present invention. In the case of liquid compositions, they may be poured repeatedly 25 through the hair until a satisfactory level of color has been attained or they may be applied to the hair by a variety of daubers until the hair is thoroughly wetted and allowed to remain until the desired depth of color is achieved. If the composition is a cream or paste, it may 30 be applied to part or all of the head of hair as desired and allowed to remain until the requisite depth of color has been attained. The procedure may be carried out either at ordinary room temperature with the head exposed to the atmosphere; or elevated temperatures may be employed 35 by means of electrically heated caps, hot towels over plastic caps, or other sources of heat.

40 Although specific embodiments of the invention have been described herein, it is not intended to limit the invention solely thereto, but to include all of the obvious variations and modifications within the spirit and scope of the appended claims.

What is claimed is:

1. A hair dye composition consisting essentially of an acid dye, a water soluble salt selected from the class 45 consisting of the chlorides, bromides, sulfates, acetates, borates, nitrates, citrates, lactates, bromates and chlorates of alkali metals, alkaline earth metals, ammonia, lower alkylamines containing from 1 to 4 carbon atoms, and mono-, di-, and tri-alkanolamines in which each alkanol group contains from 2 to 3 carbon atoms, said salt being chemically inert to the hair and to the remaining ingredients of the composition, the ratio of dye to salt being from 1:1 to 1:20000 by weight, and a free base in an amount sufficient to produce a pH of 8.5 to 12.5 in an aqueous solution containing the composition.

2. A hair dye composition consisting essentially of an acid dye, a water soluble salt selected from the class 60 consisting of the chlorides, bromides, sulfates, acetates, borates, nitrates, citrates, lactates, bromates and chlorates of alkali metals, alkaline earth metals, ammonia, lower alkylamines containing from 1 to 4 carbon atoms, and mono-, di-, and tri-alkanolamines in which each alkanol group contains from 2 to 3 carbon atoms, said salt being chemically inert to the hair and to the remaining ingredients of the composition, the ratio of dye to salt being from 1:1 to 1:20000 by weight, and a free base in an amount sufficient to produce a pH of 8.5 to 12.5 in an aqueous solution containing the composition, said salt being selected from the class consisting of sodium hydroxide, sodium carbonate, 2-amino-2-methyl-1,3-propanediol, ammonium hydroxide, and monoethanolamine, said composition containing in addition from 20% to 400%, based on the total weight of said dye and said salt, of an organic material selected from the class consisting of n-butyl alcohol, n-amyl alcohol, n-octyl alcohol,

benzyl alcohol, terephthalyl alcohol, phenyl ethyl alcohol, cyclohexanone, tetrahydrofuran, aniline, chlorobenzene, camphor, xylene and toluene, said organic material being one which forms a separate phase when mixed with water in the ratio 4 parts by weight of organic material to 10 parts of water at 25° C., and which, in contact with a separate aqueous phase containing said dye, said salt, and said free base, extracts a portion only of said dye therefrom in three hours at 25° C.
